UNITED STATES PATENT OFFICE.

HANS OTTO SWOBODA, OF NEW YORK, N. Y., ASSIGNOR TO THE GENERAL INCANDESCENT ARC LIGHT COMPANY, OF NEW YORK.

ELECTRIC-ARC LAMP.

SPECIFICATION forming part of Letters Patent No. 635,819, dated October 31, 1899.

Application filed August 29, 1898. Serial No. 689,806. (No model.)

To all whom it may concern:

Be it known that I, HANS OTTO SWOBODA, a subject of the Emperor of Germany, residing at New York city, county and State of New York, have invented new and useful Improvements in Electric-Arc Lamps, of which the following is a specification.

5 My invention relates generally to an improved method of mounting electromagnets which are subjected to the action of alternating currents and finds its most important application in the mounting of the feed-magnets of an electric-arc lamp designed to be operated by alternating currents. As is well known, the rapid reversals of action in the alternating current used for operating such lamps cause the feed-magnets to vibrate so rapidly that a humming or chattering noise is produced. If the magnet or magnets are rigidly mounted on the supporting-frame of the lamp or on a base rigidly attached to said frame, the vibrations of the magnet are transmitted to the entire lamp and the sound is greatly magnified, so as to become highly objectionable, especially when the lamp is used for indoor illumination. Moreover, the vibrations thus transmitted to the lamp interfere with the steadiness of the light and the smoothness of the feeding action. I over- 20 come this difficulty by mounting said feed-magnet on a flexible base, and preferably interpose sound-deadening material at the point of attachment to the supporting-frame and at every point of possible contact between the magnet or its projections and said supporting-frame. Obviously any kind of a feeding device may be employed to cause the feeding of the carbons under the control of said magnet; but I preferably employ a clutch 25 of the general description illustrated and described in application, Serial No. 667,672, filed February 17, 1898, by Sigmund Bergmann. Inasmuch as the movable core or armature of the solenoid-magnet commonly used becomes rigidly connected with said magnet under the action of the magnetism when the current is passed through the solenoid, it also becomes necessary to interpose a vibration-deadening connection between said armature and the other portions of the feed mechanism of the lamp, and thus the feed-magnets and all parts

which must necessarily experience the same vibrations are insulated completely from the other portions of the lamp so far as the transmission of said vibrations is concerned.

55

The preferred form of my invention is illustrated in the accompanying sheets of drawings, in which—

Figure 1 is a side elevation of a feed mechanism, showing a portion of the supporting-frame of the lamp and my improved method of mounting the magnets. Fig. 2 is a front elevation of the same. Fig. 3 is a section on the plane of Fig. 1, and Fig. 4 is a section on the plane of Fig. 2, said sectional views being designed to bring out clearly the attachment of the core or armature of the feed-magnet to the feed mechanism. Fig. 5 is a detail showing a modified form of a spring-plate attachment. Figs. 6 and 7 illustrate modified forms of armature-connecting springs.

Throughout the drawings like reference-figures refer to like parts.

1 represents the lower supporting-plate of the lamp.

75

2 represents the upper supporting-plate.

3 3 represent the feed-magnet, which, as shown, consists of two solenoids, but which obviously might be of any form.

4 4, &c., represent the studs, which form 80 the inclosing frame of the magnet.

5 is a flexible spring-plate, to which the magnet is attached by the studs 4 or otherwise, preferably having a curved portion 6 and a reversed portion 7, which latter is attached to the plate 2 by any convenient means, such as the screw-bolts 8 8, passing through the lug 9 on plate 2 and having the nuts 10 10.

11 and 12 represent interposed layers of sound-deadening material which are located 85 between the flexible plate and the supporting-plate 2 and nut 10. Sleeves or thimbles 13 13 of the same material may surround bolts 8 8. Various kinds of material may be used for this purpose of deadening the sound and other vibrations—such as asbestos, indurated fiber, paper, &c., or other non-resonant material. In case the coils of the magnet and their connections are not insulated completely 90 from the spool or other support the sound-deadening material should also be an electrically-insulating material; but it is obvious 100

that nearly every form of such material, such as mentioned above, is also an electrically-insulating material.

In order to prevent too extensive vibrations of the magnet and to prevent sagging of the same beyond a certain extent, stops 14 and 15 or other projections are extended to within a short distance of the plates 1 and 2, and in order to deaden and prevent the creation of noise and the transmission of vibrations to the supporting-frame similar pieces of sound-deadening material 16 and 17 are located at all points of possible contact.

The magnets 3 3 have the U-shaped armature or double core 23, which is supported by the spring 26, attached to its middle portion by the preferably hinged joint 29. The upper end of this spring 26 is attached to the depending rod 28, mounted in the cross-piece 21, to one end of which is connected the dash-pot 24, while the other end is connected to the clutch 19 by the rods 30 30 or other equivalent device.

The mechanism above described is guided by the rod 27, fastened to the plate 2 and having a telescoping joint with a prolongation of the part 28.

A modified form of supporting spring-plate 5 is shown in Fig. 5, the bent portion 6 of said spring-plate being attached directly to the side of the lug 9^a by means of a screw 8^a, with the interposition of sound-deadening material in the same manner as described with reference to Figs. 1 and 2.

Figs. 6 and 7 illustrate modified forms of the springs 26^a and 26^b, and it is evident that still other forms of spring might be employed, the point to be kept in view being only to provide a spring which will have sufficient flexibility to prevent the transmission of vibrations, while at the same time it shall have sufficient stiffness to render the clutch-operating mechanism responsive to movements of the armature 23.

The other parts of the lamp shown in the drawings for clearness are the carbon-carrier 18, clutch-supporting spring 20, lamp side rods 24 24, and clutch-tripping lugs 25 25.

The mode of operation of my invention is clear from the foregoing. However rapidly the feed-magnets may vibrate under the action of the alternating currents, those vibrations will not be transmitted to the lamp, nor will the sounds produced by such vibrations be magnified by communication to and amplification by the metallic lamp structure, as is the case in ordinary lamps.

Evidently various changes could be made in the details of construction shown without departing from the spirit and scope of my invention, so long as the central idea thereof—to wit, the interposition of a yielding medium at every point of contact between the magnet and the lamp-frame—is retained.

The prime object of my invention, as before stated, is to prevent the transmission of vibrations from the feed-magnets and their

armature to the other portion of the lamp, and this is secured by interposing springs or soft non-resonant material at every point of attachment and possible contact between said feed-magnet and armature and the other portions of the lamp. While every material which will prevent transmission of such vibrations is included in my invention, I shall refer to such material by the expression "sound-deadening material," inasmuch as the most noticeable result of such vibrations is the series of sounds, which it is the object of my invention to eliminate from the operation of the lamp.

Having therefore described my invention, what I claim as new, and desire to protect by Letters Patent, is—

1. In an electric-arc lamp, the combination of the supporting-frame, the feed-magnet, and a horizontally-disposed spring-plate from which said magnet is suspended, substantially as described.

2. In an electric-arc lamp the combination of the supporting-frame, the feed-magnet, the flexible plate on which said magnet is mounted and sound-deadening material interposed between said plate and frame at the point of attachment thereof, substantially as described.

3. In an electric-arc lamp the combination of the supporting-frame having an upper and lower plate, the feed-magnet supported between the same by a flexible mounting, and sound-deadening material located at all points of possible contact between said magnet and said frame-plates, and interposed between the same, substantially as described.

4. In an electric-arc lamp the combination of the supporting-frame, the feed-magnets supported thereon by a flexible sound-deadening mounting, and a mass of sound-deadening material located on said supporting-frame under said magnet at the points of possible contact in case of a sagging of said magnet, substantially as described.

5. In an electric-arc lamp, the combination of the supporting-frame, the feed-magnet, and the horizontally-disposed curved spring-plate suspending the magnet and attached at its curved end to the supporting-frame, substantially as described.

6. In an electric-arc lamp, the combination of the supporting-frame having an upper and lower plate, the feed-magnets supported and suspended between the same by horizontally-disposed flexible mounting and stops extending from said magnets to within a short distance of one or more of said plates, substantially as described.

7. In an electric-arc lamp the combination of the supporting-frame having an upper and lower plate, the feed-magnet supported between the same by a flexible mounting, and stops extending from said magnet to within a short distance of one or more of said plates, together with sound-deadening material located at all possible points of contact between

said stops and said plates, substantially as described.

8. In an electric-arc lamp, the combination of the supporting-frame, the feed-magnet, and a horizontally-disposed flexible mounting and suspending device for the feed-magnet, the clutch mechanism, the feed-magnet armature, and a flexible connection between the armature and the clutch mechanism, substantially as described.

9. In an electric lamp, the combination of the supporting-frame, the feed-magnet, pro-

vided with an armature having a movement in the longitudinal axis of the lamp, and a horizontally-disposed spring-plate connected at one end to the supporting-frame and at the other end to said magnet, substantially as described.

In testimony whereof I affix my signature in the presence of two witnesses.

HANS OTTO SWOBODA.
